UNITED STATES PATENT OFFICE.

EVALD M. MATTSON, OF INMAN, KANSAS.

ROTARY VALVE MECHANISM FOR ENGINES.

1,271,344.

Specification of Letters Patent.

Patented July 2, 1918.

Application filed August 16, 1916. Serial No. 115,341.

To all whom it may concern:

Be it known that I, EVALD M. MATTSON, a citizen of the United States, residing at Inman, in the county of McPherson and 5 State of Kansas, have invented new and useful Improvements in Rotary Valve Mechanism for Engines, of which the following is a specification.

This invention relates to rotary valve mechanism for engines, the broad object in view 10 being to provide in connection with a multiple cylinder engine, a combined inlet and exhaust valve for each pair of adjacently located cylinders. In a four cylinder, four 15 cycle engine, two of such valves will be used and be driven from any suitable part of the engine such as a shaft geared to the engine shaft.

One of the principal objects of the present 20 invention is to provide a compression band mounting of the rotary valve which will prevent leakage of fresh charges or burned charges of fuel and which will also prevent the drawing in of cold air during the operation of the valve mechanism and the subsequent delivery of said air to the combustion chambers of the cylinders.

A further object in view is to provide a 25 valve and operating mechanism therefor which will operate silently, positively, which will admit of large valve openings and which will not have to be lifted or shifted to allow the exhaust or burned gases to escape.

30 With the above and other objects in view, the invention consists in the novel construction, combination and arrangement, herein fully described, illustrated and claimed.

In the accompanying drawings:

40 Figure 1 is a side elevation of an engine showing the improved valve mechanism in its applied relation thereto.

Fig. 2 is a plan view of the same.

45 Fig. 3 is a horizontal section taken through the valve chambers.

Fig. 4 is a vertical diametrical section through the valve chambers.

Fig. 5 is a detail view of one of the valves.

50 Fig. 6 is a similar view of one of the compression bands.

Fig. 7 is a section through one of the valves taken in line with the exhaust port.

Fig. 8 is a similar view taken in line with the inlet port.

55 Referring to the drawings, *a* designates generally a four cylinder, four cycle inter-

nal combustion engine in connection with which the improved valve mechanism is shown.

In carrying out the invention, for each 60 two adjacent cylinders, I employ a combined intake and exhaust valve casing 1. Both of these valves casings communicate at the top with an exhaust pipe 2 and at the bottom with an intake pipe or manifold 3 extending from any suitable form of carbureter 4.

Each of the valve chambers 1 is of cylindrical formation as shown and contains a valve 5 which is both an intake and an exhaust valve, the body of the valve being formed with an L-shaped exhaust passage 6 which has an outlet port 7 in the top wall thereof and an inlet port 8 in the side or periphery thereof. Each valve body also 70 comprises an inlet passage 9 having an inlet port 10 in the bottom of the valve and an outlet port 11 in the periphery of the valve body. By reference to Fig. 1 it will be observed that the outlet ports 7 of the exhaust 80 passages 6 communicate with the exhaust pipe or manifold 2, while the inlet ports 10 of the valve communicate with the intake manifold 3 at the bottom of the valve chambers. Therefore the fresh charges of mixture are admitted into the bottom of each 85 valve chamber and valve and then laterally into the cylinders while the exhaust is emitted laterally from the cylinders into the valve chambers and valves, passing out 90 through the top of the valve and valve chamber into the exhaust manifold 2.

The valves are mounted on downwardly extending shafts 12 which are shown as provided at their lower extremities with gears 95 13 meshing with other gears 14 on a counter-shaft 15 geared to the engine shaft, the arrangement shown, providing for the rotation of the valves in opposite directions, which I prefer although it will of course be obvious 100 that both of the valves may be geared to operate in the same direction.

In order to obtain fluid tight compression, I provide in connection with each of said valves, a compression band 16 of the split 105 variety, the same being divided transversely at the point 17. Projecting outwardly from the band 16 are cylindrical tubular nipples or extensions 18 adapted to fit into the engine ports in the cylinders, each of said tubular extensions 18 being formed with a groove 110 or seat in which is placed a split expandable

packing ring 19 similar to the rings now in common use on the pistons of internal combustion engines. Adjacent to the split 17 in the ring, one end of the latter is provided with a bridge piece 20 secured to one end of the ring and over-lapping the other extremity of the ring and having connected to the free edge thereof a contractile spring 21 also attached to the body of the ring 16 10 and serving to contract the ring 16 in size causing it to closely fit around the periphery of the valve. The compression band 16 is held in fixed relation to the valve casing 1 by means of a suitable fastener 22 such as a 15 bolt.

From the foregoing description taken in connection with the accompanying drawings it will now be understood that each valve 20 works in conjunction with two cylinders and takes care of both the intake and the exhaust of both cylinders. The ports of each valve are of course so arranged and located with respect to each other as to enable charges to be delivered at the proper periods to the 25 cylinders and the exhaust gases liberated at the proper periods therefrom. The expansion ring prevents leakage of the fresh charges as well as the exhaust or burned gases and also excludes atmospheric air from 30 the combustion chambers.

I claim:

1. The combination with a multiple cylinder engine having intake and exhaust ports, of a cylindrical valve casing common 35 to adjacent cylinders and provided in its bottom face with an intake port and provided in its top face with an exhaust port, a positively driven combined intake and exhaust valve rotatably mounted in said casing and provided with an inlet passage entering the bottom of the valve body and

opening through the periphery thereof and an exhaust passage entering through the periphery of the valve body and opening out through the top thereof, and an expansion 45 compression band interposed between the periphery of the valve body and the inner wall of the valve chamber, said band having projecting tubular nipples fitting into said cylinder ports, means for contracting said compression band around the body of the valve, and a bolt extending from said band through a hole in the wall of the valve casing to prevent rotation of said band. 50

2. The combination with a multiple cylinder engine having intake and exhaust ports, of a cylindrical valve casing common to adjacent cylinders and provided in its bottom face with an intake port and provided in its top face with an exhaust port, a 60 positively driven combined intake and exhaust valve rotatably mounted in said casing and provided with an inlet passage entering the bottom of the valve body and opening through the periphery thereof and 65 an exhaust passage entering through the periphery of the valve body and opening out through the top thereof, and an expansion compression band interposed between the periphery of the valve body and the inner 70 wall of the valve chamber, said band having projecting tubular nipples fitting into said cylinder ports, means for contracting said compression band around the body of the valve, and a bolt extending from said band 75 through a hole in the wall of the valve casing to prevent rotation of said band, and expansion packing rings surrounding said nipples.

In testimony whereof I affix my signature. 80

EVALD M. MATTSON.
